CLAIM

What is claimed is the ornamental design for a faucet handle, as shown and described.

DESCRIPTION

FIG. 1 is a perspective view of a faucet handle shown on a broken line representation of a faucet body;

FIG. 2 is a front view of the faucet handle;

FIG. 3 is a right side view thereof, the left side view being a mirror image thereof;

FIG. 4 is a rear view thereof;

FIG. 5 is a top view thereof; and,

FIG. 6 is a bottom view thereof.

The portions shown in broken lines are included to show environment and form no part of the claimed design
